Inventor:
Tillman Cahn,
By *Hotchkiss*,
Attorney.

UNITED STATES PATENT OFFICE

TILLMAN CAHN, OF ELKINS PARK, PENNSYLVANIA, ASSIGNOR TO PIONEER SUSPENDER COMPANY, A CORPORATION OF PENNSYLVANIA

GARTER

Application filed July 30, 1930. Serial No. 471,659.

The invention relates to garters, and is especially directed to the cast-off fastener associated therewith. The invention is particularly applicable to the type of garter for men known as wide-web pad garter.

This type of garter now in common use comprises a pad to which is permanently secured one end of a wide web leg band, to the lower part of the pad is also secured the stocking clasp, and upon the face of the pad is provided one element of the cast-off fastener. This element comprises a headed post mounted upon a slotted plate, which plate is secured to the pad by stitching. The post is adapted to cooperate with a metal loop member secured to the free end of the leg band.

The pad is frequently formed with a leather front face, a fabric back face with a layer or layers of suitable material interposed between said front and back face. These several layers are all stitched together and the post member is then stitched through all the layers.

The present invention comprises a loop member in the form of a horse-shoe, having two prongs which pass through the front layer and one or more intermediate layers of the pad formation and then cooperate and clench with a slotted plate positioned between certain of said layers, so that said loop member is firmly clamped with two or more layers of the pad formation leaving one or more inner or under layers unimpaired, that is having no metal projecting therethrough.

Referring to the drawings which illustrate merely by way of example, a suitable embodiment of the invention:—

Fig. 1 is an elevation.

Fig. 2 is a fragmentary section on enlarged scale.

Figs. 3 and 4 are details in perspective on a still larger scale.

Similar numerals refer to similar parts throughout the several views.

In accordance with the present invention, a loop member 7 is provided, preferably in the form of a horseshoe having its axis slightly inclined to the horizontal, the open end or heel of which is directed toward the edge or side of the pad 8 to which the leg band 9 is

permanently secured. This member 7 is provided with two points or prongs 10 extending from the outside margins thereof and in close proximity with the heel. These points are bent at right angles to the general plane 55 of the member 7 and are inserted through the leather layer 11, forming the front face of the pad, or they may project through this front layer and the next adjacent layer 12. A thin metal plate 13 is provided with slots 60 14 registering with the said points or prongs 10 for receiving the points as they project through the layer or layers. The points are then bent over into the plane of the plate and thus clinched therewith. The plate 13 is 65 preferably provided with a depressed portion 15 for receiving the points 10 when bent over or clenched. After which the other layers of the pad are assembled and stitched together. It should also be noted that the 70 portions of the loop member adjacent the points and the heel, are brought into close contact with the front surface of layer 11 of the pad, while the balance of the loop formation is slightly raised above said surface and 75 extends forwardly in a plane approximately parallel thereto.

The other element of the cast-off comprises a slotted member 16 secured by an adjustable loop 17 formed in the free end of the leg 80 band 9. This slotted member however instead of having a post-engaging loop, is provided with a hook formation 18 for engaging the slightly raised portion 19 of the loop or horse-shoe formation 7. This hook is also provided with an offset or shoulder, as at 20, in order to reduce the danger of accidental disengagement from the loop or horse-shoe member 7. 85

It will thus be seen that the loop or horse-shoe member is easily and securely attached to the pad, without the expensive process of stitching, is entirely covered on the underside thereof by the inner or under layer or 90 layers 21, of the pad and that its front curved formation allows the hook 18 of the other element to swing in a substantial arc in order to permit the garter to assume the desired direction of set. The connecting elements lie 95 100

flatter upon the leg and are much easier to manipulate.

What I claim is:—

1. A garter comprising a pad, a leg band having one end permanently secured thereto, disengageable connecting elements, comprising a hook member secured to the free end of the leg band, a loop element of horse-shoe formation and a slotted plate, the loop element provided with points near the heel thereof adapted to pass through a pad layer and through the slots in the plate and clench therewith.
2. A garter comprising a pad, a leg band having one end permanently secured thereto, a stocking clasp also secured thereto, disengageable connecting elements, comprising a hook member secured to the free end of the leg band, a loop element of horse-shoe formation and a slotted plate, the loop element provided with points near the heel thereof adapted to pass through certain layers of the pad, and through the slots in the plate and clench therewith, the said slotted plate having a depressed portion between the slots for receiving the points when clenched therewith.
3. A garter comprising a pad, a leg band having one end permanently secured thereto, a stocking clasp also secured thereto, disengageable connecting elements, comprising a hook member secured to the free end of the leg band, a loop element of horse-shoe formation and a slotted plate, the loop element provided with points near the heel thereof adapted to pass through certain layers of the pad, and through the slots in the plate and clench therewith, said loop element having a portion at the heel end adapted to lie flat against the front surface of the pad while a portion at the loop end is slightly raised therefrom.
4. A garter comprising a pad, a leg band having one end permanently secured thereto, a stocking clasp also secured thereto, and disengageable connecting elements comprising a hook member secured to the free end of the leg band, and a loop element comprising a substantially flat plate of horse-shoe formation having straight rear margins and lugs extending from the outer side margins slightly spaced from said rear margins.

TILLMAN CAHN.
